AIR CLEANING APPARATUS

Richard M. Smith, Detroit, Mich., assignor of
one-half to Herbert A. Stevenson, Detroit,
Mich.

Application December 29, 1937, Serial No. 182,311

9 Claims. (Cl. 261—7)

This invention relates broadly to new and useful improvements in apparatus for separating out of a gas or air stream certain foreign matter contained therein and refers more particularly to an apparatus for removing and retaining out of an air stream solid matter carried in suspension therein.

One object of the invention is to provide an apparatus which will effectively and efficiently entrap particles of solid foreign matter carried in or by the air stream and withhold the same therefrom as the stream passes through and from a confined space or region.

Another object is to deposit the foreign matter in the liquid of a liquid containing chamber so that the matter can not reenter the air stream.

Another object is to provide novel liquid employing means for separating out the foreign matter and to provide means for reusing the liquid.

Another object is to provide means for effectively removing the entrapped foreign matter.

Another object is to provide for disclosing the state of the apparatus and indicating when the apparatus should be emptied of foreign matter.

Another object is to provide means to remove moisture entrapped and eliminate foreign matter which might be carried in the discharging air stream and substantially dry the air.

Another object is to provide means for cleaning the moisture entrapping means of collected foreign matter.

Another object is to provide means for storing and reusing the dirt eliminating liquid.

The invention consists in the improved construction and combination of parts and their aggroupment in cooperative relation, to be more fully described hereinafter and the novelty of which will be particularly pointed out and distinctly claimed.

In the accompanying drawings, to be taken as a part of this specification, there are fully and clearly illustrated certain apparatuses or structures embodying the invention, in which drawings—

Figure 1 is a top plan view of the exterior of the complete apparatus;

Fig. 2 is a view thereof in side elevation looking from right to left, facing Fig. 1;

Fig. 3 is an enlarged view in elevation and partly in section looking from left to right, facing Fig. 2;

Fig. 4 is a detail view in perspective of a separator or baffle member employed in the apparatus;

Fig. 5 is an enlarged detail view partly in section of a spray member;

Fig. 6 is an enlarged detail view in front elevation of a baffle or flow intercepting member;

Fig. 7 is a view in section on the line 7—7 of Fig. 6;

Fig. 8 is an enlarged detail view in section of a closure seal;

Fig. 9 is a view in longitudinal vertical section of part of the apparatus, but showing another form of eliminating means;

Fig. 10 is a view in section on the line 10—10 of Fig. 9;

Fig. 11 is a top plan view of the apparatus but with parts broken away to show the internal construction and showing still another form of eliminating means, and

Fig. 12 is a view in section of part of the apparatus, on the line 12—12 of Fig. 11.

Referring to the drawings, Figs. 1 to 8 inclusive, by characters of reference, 1 designates a casing or container which is preferably rectangular in horizontal cross-section. The side walls 2 of the casing may be reinforced by enclosing channel frame members 3 welded or otherwise secured to the casing side walls 2 which are preferably of sheet metal also welded or otherwise secured and sealed together at the corners. The side walls 2 are bounded at their upper edge by a surrounding and reinforcing angle-iron frame member 4 having an outwardly extending flange.

Positioned within the chamber or reservoir 4^a of the outer container 1 there is an inner casing or container 5 preferably also rectangular in horizontal cross-section and which is centrally located, having its side walls 6 spaced equally from the adjacent container walls 2. Closing the horizontal space between the walls 2 and 6 there is a top cover member 6^a which seats on frame member 4 and a bottom wall 7 having a rectangular central opening registering with, conforming to and of substantially equal size to the lower end of inner casing 5. The wall 7 may be welded or otherwise rigidly sealed at its outer and inner peripheries to the walls 2 and 6 respectively. The upper edge of inner casing wall 6 is bounded by a reinforcing angle-iron 8 having an outward extending flange to receive the horizontal marginal lower edge flange 9 of a hood or cover member 10 which closes the top of casing 5. The member 10 is preferably in the form of a half cylinder, having a semi-circular curved top wall 11 closed at its ends by vertical walls 12 and 13. The walls 11, 12 and 13 terminate in the flange 9 which is bolted

or otherwise secured to the angle member 8. Extending outward from the top edge of wall 6 and preferably interposed in the length of angle member 8 are opposite supporting angle pads or members 14 positioned at the bases of walls 12 and 13 and substantially at the center line of curvature of wall 11. Mounted on the oppositely disposed members 14 external of end walls 12 and 13 are journal bearing members 15 which may be bolted or otherwise secured to pad members 14. The end wall 13 has air or gas inlet means 16 such as a pipe or conduit opening through and secured and sealed to the wall 13 to provide communication from a room or other space to the chamber 17 within the hood member 10. An outlet pipe or conduit 18 opens through the cover member 6^a to which it is secured and sealed and provides an outlet flue or passageway leading from the chamber 4^a to any desired place of discharge, such as the outside atmosphere. Opposite the inlet 16, the wall 12 has laterally spaced outlet flues or conduits 18^a which are turned downward to and which open through cover member 6^a into chamber 4^a. Substantially in the plane of wall 12 there is a partition wall or baffle member 18^b and a partition or closure wall 18^c, the wall 18^b extending downward from the top wall 6^a and closing the space between the containers but terminating short of bottom wall 7 to provide a passageway.

Extending through aligned openings in end walls 12, 13, beneath conduits 17 and 18 and supported and journaled in bearing members 15, is a shaft 19 which projects outward from wall 13 to a point beyond the casing wall 2 to receive a drive wheel 20 for a chain drive 21 or the like. Secured on the shaft 19 for rotation therewith are a plurality of baffle or flow intercepting foraminous members 22 which are shown in detail in Figs. 6 and 7. Each of members 22 preferably comprises a circular frame member 23 such as an angle iron having a vertical flange and a continuous surrounding flange projecting in the direction of air flow or toward the outlet wall 12. Concentric with member 23 there is a circular plate or pad member 24 having a central aperture therethrough receiving the shaft 19. Extending radially from and secured to member 24 are a plurality of spokes or ribs 25 preferably angle irons set at ninety degrees and each having one flange in the plane of the wheel or baffle member 22 and the other flange directed toward the inlet wall 13. Filling the space within the frame member 23 and riveted or otherwise secured to the vertical flange thereof is a foraminous or perforate member 26 preferably a plate of metallic sheet material having a multiplicity of closely spaced circular apertures 27 therethrough. The perforate member 26 is also preferably riveted or otherwise secured to the flanges of common plane of the angle members 25 and therefore is positioned between the members 23 and 25. Secured to the opposite or outlet face of member 26 from pad member 24 and also to the pad member is a hub member 28 which receives and is secured to the shaft 19 as by set screws or the like. The baffle members are spaced longitudinally of the shaft 19 and are each of a diameter to substantially close with the inside surface of hood member wall 11 throughout their upper half or semi-circular area and to have their lower or under halves dipping into the inner container 5.

The reservoir formed by container 5 has a bottom wall or hopper 29 of downward converging pyramidal form terminating in a rectangular, 75

horizontally continuous and downward extending flange 30. Secured and sealed to the bottom edge of flange 30 is a plate member 31 having a central circular aperture 32 therethrough. On the underside of member 31 and concentric with aperture 32 are a pair of spaced concentric rings 33 forming a packing member receiving channel therebetween which contains packing material 34. The opening 32 is closed by a conical bell member 35 having a bottom plate 36 terminating at its marginal edge in a cylindrical flange 37 which enters the channel of rings 33 and seats against the packing material 34 to seal the opening 32. Secured to the upper end portion of member 35 is a stem or rod member 38 having a longitudinal slot 39 through which the shaft 19 extends and above which is a screw-threaded portion 40. The bell member 39 can be raised and lowered by a hand wheel 41 threaded onto portion 40 and seating on a plate member 42 through which portion 40 extends. A frame work 43 of inverted U-shaped form supports the plate member 42. The frame work 43 preferably comprises a pair of vertical channel members 44 joined at their upper ends or bridged by parallel horizontal channel members 45. The plate member 42 is secured to and rests upon the top flanges of members 45. The vertical frame members 44 are supported by or on the cover member 11 by brackets or arms 46 which are welded or otherwise secured thereto.

Within the inner casing 5 there are a plurality of separating means 46^a, of which one is shown in detail in Fig. 4. The means 46^a are in two groups comprising an upper set and a lower set. Each of the means 46^a is preferably a sheet material member or louvre substantially rectangular, the upper set having side walls 47 extending downward and converging inwardly from the chamber wall 6. The walls 47 lie in planes substantially parallel to the side walls of the bottom wall 29. Each of the walls 47 terminates in a continuous downward extending flange 48, the flanges being substantially in vertical alignment to provide a central space or open-ended chamber 49 defined by the vertically registering apertures through the flanges. Each of the flanges 48 terminates closely adjacent the top edge of the next lower flange 48 so as to provide a narrow horizontally continuous passageway or throat 50 establishing communication between the chamber 49 and an outwardly positioned and upwardly and outwardly diverging or inclined surrounding chamber 51 of which there is one for each throat 50 and which are separated by the walls 47. Each of the walls 47 is secured along its upper edge portion to the wall 6 and has through its upper edge portion a plurality of spaced substantially rectangular apertures or ports 52 so that the chambers 51 are in direct communication with each other and the uppermost chamber 51 is open directly into the inner chamber 49. The lowermost wall 47 cooperates with the uppermost of the walls 53 of the lower set 54 of the separating means to provide the lowermost of the chambers 51. The walls 53 are substantially parallel to walls 47 and converge downward and inward from the casing wall 6, being respectively secured and sealed thereto as by welding along their upper edge portions. The walls 53 extend inward beyond flanges 48 and each terminates in a downward continuous rectangular flange 55 which is substantially aligned with the bottom wall flange 30, thus providing a lower trap or pocket surrounding the bell member 35. This pocket is surrounded by upwardly and

outwardly inclined or diverging rectangular chambers 56 which are in communication with the pocket and inner chamber 49 through the narrow continuous horizontal passageways or throats 57 between adjacent flanges 55. The upper edge portion of each of the separating chamber members 53 also has a plurality of equally spaced rectangular openings or recesses 52 which permit direct communication between the superposed chambers 56 and 51.

The containers 1 and 5 and the structure above defined are supported on corner posts or columns 58 having supporting base members 59 which rest on and may be secured to the floor or other foundation 60. The columns 58 beneath the inlet conduits 16 serve to support an elevated table or platform 61. Mounted on the platform 61 is a liquid pump 62 and an electric driving motor 63 geared to the pump by a drive shaft 64. The motor 63 is also connected to a speed reducing gear box 65 having a drive pulley 66 which receives the drive chain 21 to rotate thereby the baffle members 22 at a speed of say about 10 R. P. M.

The inlet to the pump is supplied by a pipe 67 having branches 68, 69, the branch 68 leading from a main or other supply (not shown) and being controlled by a manual shut-off valve 70. The branch 68 also has a shut-off valve, designated 71, and opens into a continuous rectangular pipe line 72 which surrounds the lower part of the container wall 2 and is connected into the interior of the casing 1, i. e., outer chamber 4^a by four pipe members 73 preferably positioned midway of the width of each side wall. The pump outlet is connected by a pipe 74 to a manifold 75 from which lead pipes 76, 77 and 78. The pipe 78 has a control valve 79 and extends upward and laterally to a manifold 80 positioned along a lower side wall portion of wall 11 and from which lead spray pipes 81, 82. The wall 11 has a pair of oppositely positioned apertures intermediate the wall 13 and the first or adjacent baffle member 22 for passage of the pipes 81, 82 therethrough. These pipes are similar, the pipe 81 being shown in detail in Fig. 5, and each has a longitudinal vertical, upward and downward directed spray or outlet slot or orifice 83 therethrough which is held in open position by spaced vertically positioned rod or wire spacer members 84. The pipes 81, 82 extend transversely through the inlet portion 84^a of chamber 17 which portion may be termed the spray chamber within which the slots 83 discharge. The pipe 76 has a control valve 85 therein and extends upward adjacent to the top of casing 1 where it is turned inward toward and opens through an aperture in wall 2 in which it is sealed. The pipe 77 also has a control valve 86 therein and extends upward adjacent a point above the topmost separating member 47 where it is turned inward toward and extends through and is sealed in aligned apertures in the casing walls 2 and 6, opening as at 87 into the inner chamber 49. The chambers 4^a and 49 are in direct communication at their upper ends by means of one or more ports 88 through the top portion of side wall 6 preferably beneath the inlet conduits 16. The outer tank 1 is provided with a liquid level gauge 89 having the usual transparent water column to indicate the level of liquid in the outer chamber 4^a.

In the return pipe 69 which feeds the pump, there are two T-fittings for branch return pipes 90, 91 positioned one above the other. The pipes 90, 91 open respectively into continuous pipe lines 92, 93 which extend around the bottom casing

wall 29. The line 92 is substantially midway of the height of wall 29 and the line 93 is therebelow. A plurality of branch pipes 94, 95 respectively lead from the lines 92, 93 at substantially right angles to the wall 29, extending therethrough and sealed therein and opening through the lowermost louvre or separating member 53 into the upward inclined space between the lower two of the louvres 53. The branch pipes 90, 91 are provided respectively with manual shut-off valves 96, 97 which control flow from the inner tank chamber 49 to the pump.

The operation of this apparatus is as follows: The inlet pipe or conduit 16 is connected to a space or chamber to have evacuated therefrom air or gas having in suspension or carrying foreign matter or particles such as dust or dirt. The outlet pipe or conduit 18 is connected to the inlet of an exhaust fan or blower (not shown) which discharges say to atmosphere or external of the room or chamber. The inlet valve 70 is opened to supply liquid such as water to the pump inlet pipe 67 and valves 85 and 86 are opened to supply water to the chambers 49 and 4^a respectively. The pump motor 62 is now started which feeds water into the inner and outer chambers and when the level in the outer chamber 4^a rises to a point, as indicated by the gauge 89, which is above the connecting pipes 73 and about halfway of the height between the bottom wall and the lower edge of baffle member 18^b, the valve 86 is closed. Water is continued to be supplied to the inner chamber 49 until it overflows through ports 88 into chamber 4^a as will be disclosed by the gauge 89, and then the motor 63 is stopped and valves 85 and 70 are closed. The valves 71 and 79 are now opened so that circulation from the outer chamber 4^a to the pump 62 and from the pump to the inner chamber 49 via the spray pipes 81, 82 can take place. The valves 96, 97 are of course closed.

If the pump motor 63 and the suction fan (not shown) for outlet conduit 18 are now started, water will be supplied by the pump 62 through conduit or pipe 78 to the manifold 80 and thence to the spray pipes 81, 82 and air will be drawn through inlet 16 into the housing chamber 17. The operation of motor 63 will also drive through the reduction gearing 65 and the chain 21, the shaft 19 thereby to rotate the baffle discs 22. The exhaust fan will draw the air through the moistened perforate disc members 22 and into the chamber 4^a through conduit members 18^a. The members 22 due to the small size of apertures 27 serve to subdivide minutely any water particles or droplets which might be entrained at the spray pipe water curtains. The air entering chamber 4^a is substantially free of foreign matter or dust and passes counterclockwise, facing Fig. 1, so that it first is required to flow downward beneath the lower edge of baffle member 18^b and simultaneously therewith making a right angle turn to flow generally toward inlet pipe 16. Before the air reaches the outlet 18, it is required to make two additional right angle turns, which three turns act to throw out of the stream any retained foreign particles. The flow of the air externally around the casing 5 within chamber 4^a tends to eliminate freezing of the water which is within the casing 5.

Before the air stream reaches the baffle members 22, it must traverse or pass through the water curtains discharging upward and downward from each of spray pipes 81, 82. These curtains issue from substantially continuous slots

so that consecutive walls of water are presented to or in the path of the air stream and entrap and deposit the dust or dirt into the water in container 5. As the air is passing through the apertures or perforations 27 in the baffle members 22, the members 22 are being rotated slowly so that dust or dirt collected on the baffle member surfaces is washed off in or by the liquid in chamber 49 of tank or container 5 so that the apertures 27 are kept open to reduce resistance to the air flow. The members 22 turn slowly enough so that the water or liquid in casing 5 is disturbed only very slightly, thereby permitting the dirt to settle or drop slowly toward the chamber bottom. The inwardly converging top separator member 47 acts to direct the sinking dust particles toward the chamber center which is also accomplished by the inward projecting portion of the top-most member 53 so that the dirt is directed away from the openings 50, 51. The low rotary speed of members 22 also permits excess water to drain off the emerging portions of members 22 so that only the minimum quantity of water to provide wetted dirt entrapping surfaces is raised by members 22 into the air stream. The water from the spray pipes overflows through the apertures 88 into the chamber 4^a for supply to the pump as above.

With the apparatus in operation, dirt will gradually fill the chamber 49 defined first by flanges 55 and then by flanges 48. As the dirt rises in the chamber, the water will be separated out of it by the louvre structure or separating means 54 and 46, the water lying between the superposed plate members 53 and 47 and passing upward through the edge apertures 52, the supported dirt squeezing out the water from the underlying dirt. The dirt in the inner chamber of container 5 will displace water therefrom which together with the spray water, will overflow into chamber 4^a. As the dirt level rises in the inner chamber, the liquid level will rise substantially proportionally in the outer chamber 4^a. The gauge 89 will therefore indicate the height of foreign matter accumulation in the inner chamber and disclose when the chamber is full and requires emptying. The cross-sectional area of chamber 4^a is sufficiently greater than the area of chamber 49 so that all of the displaced liquid will not block or close off the passageway beneath the lower end of partition 18^b.

When the inner chamber is filled with dirt to capacity, the valves 71 and 79 are closed and valves 96 and 86 are opened. At this time the greater part of the liquid originally in the inner chamber will have been displaced into the chamber 4^a. The opening of valve 96 will supply the pump with liquid from the spaces between the louvres and with the surface liquid overlying the dirt pile. Due to the flanges 48 and 55 and the upward inclination of the louvre plate members, substantially no dirt will be admitted to the pump feed line or pipe. The withdrawn liquid or water will be discharged by the pump through the pipe 76 into the outer chamber 4^a. When the dirt has been substantially dehydrated and all the liquid removed from above the pipe inlets 94, then the valve 96 is closed and valve 97 is opened and the final stage of liquid removal is performed with the result that very little water is retained by the dirt or sludge, i. e., only about seven per cent of the water is lost and requires replacement. The agitation of the water in the inner chamber by the members 22 and the water curtains serves to prevent freezing of the water

in cold weather. Freezing in the outer chamber 4^a is prevented by the rapid circulation of the water therethrough.

When all of the free water is withdrawn finally through pipe 91, the pump is stopped and valve 97 is closed. The hand wheel 41 is now turned to lower the bell closure member 35 and the eliminated dirt is dumped from the inner chamber. The exhaust or suction fan is of course stopped when the apparatus requires emptying. The filling of the chamber 4^a acts to wash down the chamber walls and remove any dirt accumulated thereon. The dirt having been emptied, the bell member 35 is closed tightly by the wheel and screw 40, the valve 86 is closed and valve 71 is opened. The pump is now started to displace the water from chamber 4^a into the interior of casing 5 via pipe 71. The deficiency of water in casing 5 is made up from the source of supply by the operation above described for initial filling of the inner casing. The apparatus is now ready for another cycle of operation, the steps of which will be apparent from the foregoing description.

Referring to Figs. 9 and 10, a modification is shown in which the baffle members and spray pipes of Figs. 1 to 8 are dispensed with and in lieu thereof, the hood member 10 is provided with consecutive spaced partition or baffle members 100, 101. The members 100, 101 fit the wall 11 and terminate in horizontal planes adjacent to but above the lower edges of wall 11 so as to provide narrow air flow passageways 102 therebeneath and above the surface of the liquid in the inner casing 5. At the lower terminal edge of members 100, 101 are spray pipes 103, 104 respectively which may be fed from the manifold 80. The pipes 103, 104 each has a downward opening narrow discharge slot or orifice 105 which extends longitudinally of the pipe and across the cover member 11. The downward discharging water curtains or baffles are not merely sprays, but there is a forced water discharge in a substantially unbroken or continuous stream from each water pipe which must be pierced by the air stream. The water curtains therefore drive the foreign entrained particles into the body of water in chamber 49 so that the particles sink downward as in the apparatus of Figs. 1 to 8.

In Figs. 11 and 12, the apparatus of Figs. 1 to 8 is provided with a different form or type of separating or baffle means in lieu of the rotating perforate discs and water curtains, the reference characters applied to Figs. 1 to 8 designating like parts in these Figs. 11 and 12. The casings 1 and 5 are closed by a top cover member 200 having transversely extending corrugations forming a series of raised downwardly open chambers or recesses 201 extending the width of casing 5 and intermediate the inlet 16 and outlet 18 which in this case open through the cover member 200. Positioned in each recess 201 is a longitudinally extending spray pipe 202 having closed ends and having laterally downward directed narrow spray slots or orifices 203 extending the width of the casing 5. Extending across the casing 5 below and in line with pipes 202, are shafts 204 which are journaled in bearings carried by the opposite side walls of casing 5 and which project at one end through the casing wall to receive gear wheels 205 which are in mesh so that the shafts are driven in unison. The pulley 20 driven by the motor driven chain or belt 21 is secured on the shaft closest the inlet 16 so that its shaft be-

comes the drive shaft for the other two shafts 204. Each of shafts 204 carries baffle means 206, preferably a multiplicity of closely spaced radially extending members of substantially equal length providing tortuous passageways and which may overlap each other longitudinally of the shaft and which provide a cylindrical moisture eliminator of interstitial form. The overflow ports or passageways 88 are positioned at a height such that the liquid level in chamber 49 will be in the plane of the shafts 204. The cylindrical eliminators 206 will therefore dip into or be submerged throughout substantially one half of their circumference in the water within chambers 49. The diameter of the eliminators 206 is preferably such that there are opposite spaces 207 at the lower edge of each recess, but so that a portion of the eliminator periphery extends into its overlying recess. The spray slots 203 are preferably so positioned that the water spray discharges both onto the rotating eliminators and also through the spaces 207 to impinge directly against the surface of the water in chamber 49 intermediate the eliminators. Thus a plurality of water curtains or baffles and also wetted eliminators are provided to intercept and remove foreign matter entrained in the air stream entering inlet conduit 16.

From the foregoing description of the various forms and types of apparatus disclosed, it will be apparent that the invention provides a highly efficient dust arrestor of low maintenance cost and applicable to foundry, cement plant, Solvay process plants and the like uses.

What is claimed and desired to be secured by Letters Patent of the United States is:

1. In an apparatus of the character described, a container having a space for liquid, said container having an inlet and an outlet for air, said inlet and said outlet being above the highest level of liquid in said space, means to intercept solid foreign matter in the air admitted to said container through said inlet, said means acting to deposit the solid matter in the liquid in said space, means within said space operable to separate the liquid from said solid matter, said last-named means comprising a plurality of overlying vertically spaced plate members extending along the inner wall of said container, said plate members extending downward and inward from the container wall, and means to withdraw substantially all of the separated liquid from said space so that the foreign matter substantially devoid of liquid can be removed from said space.

2. In an apparatus of the character described, a container having a space for liquid, said container having an inlet and an outlet for air, said inlet and said outlet being above the highest level of liquid in said space, means to intercept solid foreign matter in the air admitted to said container through said inlet, said means acting to deposit the solid matter in the liquid in said space, means within said space operable to separate the liquid from said solid matter, said last-named means comprising a plurality of overlying vertically spaced plate members extending along the inner wall of said container, said plate members extending downward and inward from the container wall, a flange extending downward from the inner edge of each plate member and terminating closely adjacent the next lower plate member, and means to withdraw substantially all of the separated liquid from said space so that the solid matter substantially devoid of liquid can be removed from said space.

3. In an apparatus of the character described, a container having a space for liquid, a container having a space for liquid and surrounding said first-named container, a hood member closing the upper end of said first-named container and having an inlet and an outlet, a plurality of baffle members within and extending across said hood member intermediate said inlet and said outlet, a plurality of continuous plate members within said first-named container and extending downward and inward from the container wall, said plate members being in overlying spaced relation to each other, each of said plate members having a continuous vertical flange extending downward from its inner edge to provide a restricted opening to the space between adjacent of said plate members, means to transfer liquid from between said plate members to said second-named container, said first-named container having an outlet opening in its bottom wall, a closure member for said outlet opening, means extending through said hood member and operatively connected to and for actuating said closure member, means to withdraw substantially all of the liquid from said first-named container, means to transfer liquid from said second-named container to said first-named container, and means indicating the liquid level in said second-named container and disclosing the quantity of solid matter in said first-named container.

4. In an apparatus of the character described, a container having a space for liquid, said container having above the liquid level an air inlet and an air outlet, means to intercept foreign particles in the air stream entering said inlet and deposit the intercepted particles into the liquid in said container, a casing surrounding and providing around said container an angular passageway, and means communicatively connecting said outlet to said passageway, said casing having an outlet from said passageway, said angular passageway serving to eliminate foreign matter from the air stream.

5. In an apparatus of the character described, a container having a space for liquid, said container having above the liquid level an air inlet and an air outlet, means to intercept foreign particles in the air stream entering said inlet and deposit the intercepted particles into the liquid in said container, a liquid containing casing surrounding and providing around said container a angular passageway above the liquid level in said casing, means for flow of liquid from said space to said passageway so that liquid displaced in said space by the entrapped particles can be retained in said passageway, and means communicatively connecting said outlet to said passageway, said casing having an outlet from said passageway, said angular passageway serving to eliminate foreign matter from the air stream.

6. In an apparatus of the character described, a container having a space for liquid, a container having a space for liquid and surrounding said first-named container, a hood member closing the upper end of said first-named container and having an inlet and an outlet, a plurality of baffle members within and extending across said hood member intermediate said inlet and said outlet, a plurality of continuous plate members within said first-named container and extending downward and inward from the container wall, said plate members being in overlying spaced relation to each other, means to transfer liquid from between said plate members to said second-named container, said first-named container

having an outlet opening in its bottom wall, a closure member for said outlet opening, means extending through said hood member and operatively connected to and for actuating said closure member, means to withdraw substantially all of the liquid from said first-named container, and means to transfer liquid from said second-named container to said first-named container.

7. In an apparatus of the character described, a container having a space for liquid, a second container having a capacity to receive the liquid from said first-named container, a hood member closing the upper end of said first-named container and having an inlet and an outlet for air, a plurality of baffle members within and extending across said hood member intermediate said inlet and said outlet, a plurality of plate members extending downward and inward in overlying spaced relation within the liquid space in said first-named container, means communicating with the space between said plate members and operable to transfer substantially all of the liquid from said first-named container to said second-named container so that the foreign matter deposited from the air into the liquid in said first-named container will be substantially devoid of liquid, means to discharge the foreign matter from said first-named container, and means to return the transferred liquid from said second-named container to said first-named container.

8. In an apparatus of the character described, an inner container having a space for liquid and having an air inlet and an air outlet above the liquid level, a plurality of baffles interposed between said inlet and said outlet, an outer container surrounding said first-named container, means to supply liquid directly to said inner con-

tainer, means to supply liquid directly to said outer container, said inner container having an overflow discharging into said outer container, a plurality of downward and inward directed overlying plate members projecting into the liquid space of said inner container, means establishing communication between the spaces between said plate members adjacent the inner container wall, said inner container having a closable opening in its bottom wall for discharge of foreign matter, means communicating with the spaces between said plate members for transferring the liquid from said inner container to said outer container, and means to return liquid from said outer container to said inner container.

9. An apparatus of the character described, comprising a container having a space for liquid and having an overflow outlet determining the maximum liquid level therein, said container having an air passageway above the liquid level, means to deposit foreign matter in the air into the liquid, a second container having a capacity to receive all of the liquid from said first-named container and communicating with said overflow, means in said first-named container to separate the foreign matter from the liquid, a conduit communicating with said first-named container and cooperable with said separating means to withdraw substantially all of the liquid from said first-named container, said conduit discharging into said second-named container, means to discharge the foreign matter from said first-named container, conduit means to return the withdrawn liquid from said second-named container to said first-named container, and means to supply additional liquid to said first-named container.

RICHARD M. SMITH.
